UNITED STATES PATENT OFFICE.

VICTOR BOVY, OF NEW YORK, N. Y.

CORSET-BUSK.

SPECIFICATION forming part of Letters Patent No. 678,713, dated July 16, 1901.

Application filed March 21, 1901. Serial No. 52,139. (No model.)

To all whom it may concern:

Be it known that I, VICTOR BOVY, a citizen of the United States, residing at New York, in the county of New York and State of New 5 York, have invented certain new and useful Improvements in Corset-Busks, of which the following is a specification, reference being had therein to the accompanying drawings.

My invention relates to improvements in 10 corset-busks, and more particularly to busks made of two parts joined or hinged together; and the object of my invention is to provide a busk which when employed in a side of a corset will permit the wearer to easily bend 15 sidewise and also leave sufficient play for forward and backward bending of the body.

In the accompanying drawings, Figure 1 represents a front view of my corset-busk; Fig. 2, a side elevation of Fig. 1.

20 The two parts A and B of a busk are respectively made of such length that the flexible joint of a busk will rest over a hip at the waist of a person wearing a corset, and this joint is formed of links of a flat-link chain, 25 preferably two links *a* and *b* of uneven length, as shown in the drawings. These links *a* and *b* are connected with each other by two concentric rivets *r r*, while the free end of links *a* and *b* is connected with one part of 30 A or B of the busk, respectively, by means of the rivets *m* and *n* and stirrups *c c'*. The two members of the longer link *b* preferably are provided with slots *s s*, in which the pin *n*, and with it part B, is free to slide upward and 35 downward or allow a limited oscillating motion of part B sidewise, as shown in Fig. 1 of the drawings.

A metal shield *d*, riveted to the inner side of the lower part A of a busk, protects the bearer 40 against the pressure of the chain-links.

Care is taken that no part of the joint *a b*

projects sidewise beyond the width of the spring parts A B.

Two of the busks just described are attached to or slid into the receptacles provided, one at each side of a corset, reaching from a hip to an armpit.

The lower part A of a busk being firmly secured in a corset, the upper portion B is thus left free to swing in a plane standing at right angles to the axles of the rivets *r r*, connecting the chain-links, but also slightly in the plane of the rivet-axes themselves, owing to the oval slots *s s* in the chain-links *b b*, which complete a universal joint at this point, the 55 chain-links in addition allowing a limited reduction in length of a busk when a person is bending sidewise, yet returning to their normal length as soon as she straightens out. A corset provided at its sides with these busks 60 will therefore leave a bearer great freedom in side, forward, and backward bending.

I am aware that prior to my invention corset-busks have been made of two parts connected by hinges, and therefore do not claim 65 this combination broadly; but

What I do claim as my invention, and desire to secure by Letters Patent, is—

The combination of part A of a busk, having a stirrup *c* engaging a chain-link *a*, and 70 having secured to its upper and inner end a shield *d* with a part B having a stirrup *c'*, chain-link *b* having slot *s*, rivets *m n* and *r*, as and for the purposes herein shown and described.

In testimony whereof I affix my signature in presence of two witnesses.

VICTOR BOVY.
